UNITED STATES PATENT OFFICE.

ALTON H. GREELEY AND CHARLES O. BARTLETT, OF CLEVELAND, OHIO.

STREET-SWEEPER.

SPECIFICATION forming part of Letters Patent No. 644,739, dated March 6, 1900.

Application filed January 28, 1898. Serial No. 668,269. (No model.)

To all whom it may concern:

Be it known that we, ALTON H. GREELEY and CHARLES O. BARTLETT, citizens of the United States, and residents of Cleveland, 5 county of Cuyahoga, State of Ohio, have invented certain new and useful Improvements in Gutter - Sweeping Machines, of which we hereby declare the following to be a full, clear, and exact description, such as will enable others skilled in the art to which it appertains to make and use the same.

Our invention has for its object to provide a sweeping-machine which is adapted to clean the gutters next to the curbing and in which 15 the sweeping-brushes are loosely supported, so as to follow inequalities in the pavement, such as gutter-crossings, &c.

Our invention consists in the features of construction and combination and arrangement of parts, as hereinafter described, shown 20 in the accompanying drawings, and specifically pointed out in the claims.

In the accompanying drawings, Figure 1 is a side elevation of our sweeping - machine. 25 Fig. 2 is a plan view thereof, a portion of the platform being broken away to show more clearly one of the brushes and its supports. Fig. 3 is a rear elevation of the machine. Fig. 4 is a side view of one of the bearings for driving-shafts. Fig. 4^a is an edge view thereof. Fig. 5 is a view in perspective of clutch-lever and connections with the clutch on rear axle. Fig. 6 is a plan view of pawl and ratchet and lever for raising the brush-shafts, 30 and Fig. 7 is an end view of the same.

In the views, 1 is a frame mounted upon rear wheel-axle 2 and front axle X.

3 is a spur-gear mounted upon the rear axle and engaging the pinion 4 upon the intermediate axle 5. A wheel 6 upon this shaft engages a corresponding bevel-wheel 7 upon a longitudinal shaft 8, which is secured within suitable bearings 9, depending from the frame.

10 and 11 are rotary brushes diagonally 45 mounted upon axial shafts 14, which are supported in bearings 13 on similar sides of triangular yokes 12, through the opposite sides of which passes the longitudinal shaft 8, upon which the yokes are supported.

50 Bevel-gears 16 upon the longitudinal shaft

engage bevel-gears 15 upon the extremities of the brush-shafts.

A universal joint is shown at 17 in each brush-shaft to afford movement of the brushes in all directions. The extremities of the movable portion of the brush-shafts are supported in bearings 18, which are connected by means of the bars 38, which pass around the brushes and are loosely held to the frame by chains 39.

It will be seen that the main axle will impart rotation to the longitudinal shaft through the intermediate gearing and thence to the brushes. It is desirable that the brushes should rise and fall easily by their own weight as they pass over uneven pavements, 65 and hence the yokes and universal joints are employed to permit this free movement, so that the brushes may always rest upon the pavement however uneven the surface.

The brushes are lifted when not in use by 70 means of drums 20 upon diagonal shafts 21 and chains 19, passing over the drums and attached to the shaft-bearings below.

A ratchet-wheel 27 is engaged by the lever 25 to turn the drum-shaft, and a pawl R securely holds the drum wherever placed.

28 are clutches of any common form mounted upon the shaft 8 to engage the loose gears 16 or release them when it is not desired to use the brushes. Another clutch 29 is employed upon 80 the axle-shaft 2, which will disengage all the gearing therefrom when desired. This clutch is shown to be operated by lever 36, bell-crank 32, and links 31 and 33 and pin 30.

Having described our invention, what we 85 claim as new, and desire to secure by Letters Patent, is—

1. In a street-sweeper, in combination; a wheeled vehicle; a longitudinal shaft mounted therein; gearing connecting said shaft with 90 an axle of the vehicle; yokes sleeved at one side on said shaft; a brush-shaft mounted diagonally in the other side of each yoke; means for vertically adjusting each brush-shaft, and a gear connection between the longitudinal shaft and each brush-shaft; substantially as described.

2. In a street-sweeper, in combination; a wheeled vehicle; a longitudinal shaft mounted therein; gearing connecting said shaft with 95 100

an axle of said machine; yokes sleeved at one side on said shaft; a brush-shaft mounted in the other side of each yoke; a gear connection between the longitudinal shaft and each brush-shaft; a universal joint in each brush-shaft; and means for vertically adjusting each brush-shaft; substantially as described.

In testimony whereof we hereunto set our hands this 15th day of December, A. D. 1897.

ALTON H. GREELEY.
CHARLES O. BARTLETT.
